UNITED STATES PATENT OFFICE.

CHARLES ARNTT, OF VANCOUVER, BRITISH COLUMBIA, CANADA.

FLOOR-OILER.

1,049,797.

Specification of Letters Patent.

Patented Jan. 7, 1913.

Application filed December 13, 1911. Serial No. 665,559.

To all whom it may concern:

Be it known that I, CHARLES ARNTT, a citizen of the United States, residing at Vancouver, in the Province of British Columbia and Dominion of Canada, have invented certain new and useful Improvements in Floor-Oilers, of which the following is a specification.

This invention relates to devices for oiling and polishing floors; and has for its object the provision of apparatus of this character that is simple in construction, will not readily clog or get out of order, and that is particularly efficient for the work for which intended.

A further object of the invention is the provision of means to effect an even distribution of oil or liquid upon the floor or surface.

To this end the invention consists in the novel construction, adaptation and combination of an oiling device for floors having a separable reservoir and a distributing chamber for the flowing oil; together with the novel devices, as will be hereinafter described in the appended specification, illustrated in the accompanying drawings, and finally set forth in the claim.

In said drawings, Figure 1 is a rear perspective view of apparatus embodying the invention. Fig. 2 is a transverse sectional view of the same. Fig. 3 is a perspective view of a detail of the invention.

Referring to the drawings, the reference numerals 5 and 6 respectively designate the front and rear retaining plates, and 7 a body of fibrous absorbent material, such as felt, clamped therebetween by bolts 8 to afford a portion 7' of the felt to project therebeyond. Each said plate is provided with one or more rows of inwardly protruding spikes 10 adapted to penetrate and prevent said felt from slipping, and as additional security the plate 5 may be formed concave on its inner face. Integrally formed, or otherwise provided on the outer face of said rear plate is a chamber 11 extending the full length of the plate. The latter is formed with a row of spaced apertures 12 positioned somewhat above the bottom of said chamber.

The numeral 13 designates a handle suitably secured to the rear plate. Fixedly secured to said handle is a reservoir 14 provided with a closure 15 through which the same may be filled and an outlet at its opposite end including a valve 16 by which the flow of oil may be controlled or discontinued. 17 is a flexible tube connection between said outlet and a tubular neck 18 opening into said chamber.

The operation of the invention may be described as follows: The oil is introduced into said reservoir whose walls may be of glass to enable the amount of oil contained therein to be readily determined, whence it flows through the valve 16 in the quantity desired to the distributing chamber 11. The provision of the apertures 12 being positioned a distance above the bottom of said chamber provides for the even distribution of the oil through all said apertures when the lower portion of the chamber is filled. The oil flowing from said apertures saturates the lower portion of the felt and is communicated and spread upon the surface worked upon by rubbing the lower exposed portion 8' of the felt thereon.

It is believed a more even distribution of the oil is accomplished through the use of two compartments for the storage and distribution of the oil, respectively, than can be attained with the use of but one.

What I claim as my invention is—

In a floor oiler, a pair of plates, a fibrous absorbent body clamped between said plates to afford two protruding edges, one of said plates provided upon its entire length and adjacent one edge thereof with a distributing chamber having communicating apertures spaced above the bottom of said chamber, conducting oil therefrom to contact with said body, an obliquely arranged operating handle upon said latter named plate, a reservoir longitudinally secured to said handle and connections including a valve between the reservoir and the chamber.

CHARLES ARNTT.
